COMBINED OIL AND GAS BURNER

1,234,088.

Specification of Letters Patent. Patented July 17, 1917.

Application filed January 12, 1917. Serial No. 142,057.

To all whom it may concern:

Be it known that I, ISAAC J. RALSTON, a citizen of the United States, residing at Brookville, in the county of Jefferson and State of Pennsylvania, have invented new and useful Improvements in Combined Oil and Gas Burners, of which the following is a specification.

This invention relates to liquid and gaseous fuel burners, and more especially to those adapted for burning gas and oil simultaneously or separately; and the object of the same is to improve the structure of a burner of this type so that the air admitted to mix with the fluid fuel may never exceed the proper proportion.

This and other objects are carried out by constructing my burner in the manner hereinafter described and claimed, and as shown in the drawings wherein—

Figure 1 is a side elevation of this burner complete, omitting the several feed pipes.

Fig. 2 is a central longitudinal section.

Fig. 3 is a cross section on the line 3—3 in Fig. 2.

This burner is intended for use in a glass flattening oven. It comprises three concentric tubes whereof the outermost constitutes the shell and extends at its forward end beyond the others so that its outlet may be flattened, as shown, to form the mouth of this burner. While I have shown it as flattened because I find the best results to follow such a shape of the mouth when the burner is used for some purposes, it will be clear that the outlet end of the shell could be given another shape for other purposes or could carry a separate element constituting the mouth of the burner, and, therefore,

I do not wish to be limited in this respect. Moreover, while I have shown the several tubes as strictly concentric, and as connected with each other and adapted to be connected with their supply pipes by certain plumbing elements, as described below, it is to be understood that this showing is simply for purposes of illustrating one effective manner in which my invention may be carried out, and I claim the widest latitude with respect thereto.

Coming now to details as shown in the drawings, the outer tube or shell 1 is rather large, and is here contracted and flattened at its front end into a mouth 2. Its rear end is threaded, as at 3, into one arm of a

T-coupling 4, and into the stem of this coupling is admitted air where indicated, probably through a pipe having a proper valve, not shown. Into the other arm of the coupling is screwed a hollow plug or bushing 5 whose bore is somewhat smaller than the interior of the shell 1.

Concentrically mounted within the shell and extending completely through the head of the T-coupling is the next smaller pipe 65 herein numbered 11, preferably threaded through the bushing 5, as at 15, and its rear extremity threaded, as at 13, into one arm of another and smaller T-coupling 14; and into the stem of this coupling is admitted 70 gas where indicated, probably through a pipe having a proper valve, not shown. The rear arm of said coupling 14 carries another and smaller hollow plug or bushing 16. The front end of the pipe 11 carries a cap 17 75 which is preferably screwed onto the same so that it may be removed and replaced by another, when desired, and this cap is provided with obliquely disposed perforations or spray holes 18, so that the gas is directed 80 out of the same and against the inner face of the shell 1 rather than forward on lines parallel with its axis and directly into what I will herein refer to as the mixing chamber 19.

The third and smallest member of the series is the central pipe 21 which is longer than either the shell or the gas pipe and extends through the bore of the latter and beyond both its ends. The rear end of the 90 pipe 21 may be threaded at 26 where it extends through the bushing 16, and in rear of the latter it may carry a nut 25. To this end oil is admitted as indicated, probably through a pipe having a proper valve, not 95 shown. The other end of this pipe is threaded, as at 22, and the cap 17 may well be screwed onto these threads. Onto its forward extremity is screwed a cap 27 of its own, this cap having strictly radial outlet perforations 100 or spray holes 28 so that the oil is delivered radially into said mixing chamber 19 on lines at right angles to the axis of the entire burner, rather than forward toward the tapered chamber 29 where the walls of the 105 shell 1 are converging toward its mouth. If the burner is thus constructed all parts are removable and interchangeable with other parts, as one skilled in the use of pipe work and couplings will understand.

I have not thought it necessary to illustrate the pipes for admitting air, gas and oil, but these will be connected where indicated and will have their individual control valves, as usual. I have supplied words to Fig. 2 to show where these several fluids are admitted, and the passages through which they flow, and from these it will be seen that oil when used flows through the central tube and out the holes 28 into the forward portion of the mixing chamber 19, in which it is broken up into fine particles or spray; whereas the air flows through the annular space between the pipe 11 and the shell, past the cap 17, and into and through the mixing chamber 19 from which the particles of oil are blown into the tapering chamber 29, and thence out the mouth 2. When gas is the fuel agent it is admitted between the innermost tubes and directed out the holes or perforations 18 in the cap 17, obliquely forward into the mixing chamber 19; and meanwhile air is admitted through the same annular channel as just described, and carries the fine streams of gas forward in the chamber 19, mixing a proper proportion of air therewith, and blowing the mixture into and through the tapering chamber 29, and out the mouth 2. When both fuel fluids are employed, the air is admixed with both, and the mixture follows the same course. It is important to note that the skirt of the cap 17 approaches the inner wall of the shell closer than the exterior of the pipe 11 which carries said cap, with the result that there is a restricted annular space 30 at this point whose total area is much smaller than the air inlet or any point between it and said space. The result is that the forcing of a given volume of air through this restricted space compresses it to an extent and imparts great speed to it, so that it is driven along the inner face of the shell forward of the cap, in a tube, as it were, which incloses or surrounds the mixing chamber 19, thereby rolling the contents of the chamber forward

therein as its periphery travels rapidly along the inner face of the shell, while its core is somewhat impeded in its progress where it travels along the threaded portion 22 of the inner tube 21. I find this manner of mixing the air with the gas to be extremely efficacious, and certainly it acts as a check to prevent the admission of too much air, while always distributing the air around the exterior of the mixing chamber. I find also that the obliquely directed spray holes 18 give better results than if the fine jets of gas were directed radially or axially within the shell; but I find that the oil ought to be injected in streams which are radial, as the disposition of the outlet holes 28 will induce.

Having thus described the invention, what is claimed as new, is:—

1. The herein described burner comprising a shell tapered at its outlet end, means for admitting air thereto, a pipe concentric with said shell, a cap whose skirt surrounds the front end of said pipe and restricts the size of the air space within the shell at this point, said cap having obliquely disposed outlet openings forward of its skirt, means for supplying one fluid fuel to said pipe, a second pipe extending along the axis of the first-named pipe and through its cap and beyond the same, and means for supplying a second fluid fuel to the second pipe.

2. The herein described burner comprising a shell tapered at its outlet end, means for admitting air thereto, a pipe concentric with said shell, a cap whose skirt surrounds the front end of said pipe and restricts the size of the air space within the shell at this point, said cap having obliquely disposed outlet openings forward of its skirt, means for supplying gas to said pipe, a second pipe extending along the axis of the first-named pipe and through and beyond its cap, a cap on the forward end of this pipe pierced with radial outlet openings, and means for supplying oil to said second pipe.

In testimony whereof I affix my signature.
ISAAC J. RALSTON.
